UNITED STATES PATENT OFFICE.

ARTHUR J. HALL, OF WILKINSBURG, PENNSYLVANIA, ASSIGNOR TO WESTINGHOUSE ELECTRIC AND MANUFACTURING COMPANY, A CORPORATION OF PENNSYLVANIA.

CONTROL APPARATUS.

1,249,748.

Specification of Letters Patent. Patented Dec. 11, 1917.

Application filed December 18, 1914. Serial No. 877,943.

To all whom it may concern:

Be it known that I, ARTHUR J. HALL, a subject of the King of Great Britain, and a resident of Wilkinsburg, in the county of Allegheny and State of Pennsylvania, have invented a new and useful Improvement in Control Apparatus, of which the following is a specification.

My invention relates to control apparatus 10 for electric motors and it has special relation to means for lubricating the contact segments of drum controllers and the like.

The object of my invention is to provide means, which shall be simple and inexpensive in construction and effective and reliable in operation, for disposing a desirable quantity of lubricating material on the contact segments of drum controllers during operation thereof.

According to my present invention, I provide, in combination with a drum controller of the usual type, means for disposing a lubricant-containing compressed gas on the contact segments, and interlocking means for 25 permitting this disposal only when the contact segments are in motion.

In the accompanying drawing, Figure 1 is a view, partially in section and partially in front elevation, of a drum controller constructed and equipped in accordance with my invention; Fig. 2 is a plan view of a portion of the structure shown in Fig. 1; Fig. 3 is a fragmentary view, in elevation, taken at right angles to Fig. 1; and Fig. 4 is a fragmentary view illustrating a modification of a portion of the apparatus illustrated in Fig. 1.

Referring to the drawing, the apparatus here shown comprises a suitable controller-40 incasing member 1 provided with a suitable top cover-member 2; a controller drum of the usual type provided with a plurality of movable contact segments 3 and a plurality of corresponding control fingers 4 that are 45 mounted upon a suitable finger-board 4'; a lubricant-containing vessel 5; a passage or pipe 6 for disposing lubricant upon the contact segments 3 in a manner to be described; a fluid-pressure system 7; and mechanical 50 interlocking means 8 that is associated with the controller drum and the fluid-pressure system 7.

The contact segments 3 are preferably mounted upon, and suitably insulated from, 55 a centrally disposed shaft member 9, to the

outer end of which an operating handle 10 is secured, in accordance with customary practice. The lubricant-containing vessel 5 is provided, to a suitable level, with a quantity of liquid lubricating material 11, and a plurality of suitable filtering screens are disposed at appropriate intervals throughout the body of the liquid. The pipe 6 extends substantially vertically alongside of the contact segments 3, and is provided with a plurality of lubricant-ejecting openings 13 opposite the respective contact segments. The fluid-pressure system 7 comprises a source of fluid pressure such as a tank 14, containing compressed air, a pipe or passage 15 communicating between the tank 14 and a point beneath the surface of the lubricating material 11, and a valve 16 that is interposed in the pipe 15. The valve 16 may be of any familiar type and is biased to a closed position for normally preventing the access of fluid pressure to the lubricant-containing vessel 5. A rod or pin 17 is adapted to operate the valve 16 when actuated by means of a cam plate 18 that is mounted upon the lower end of the controller shaft 9. The plate 18 is provided with a substantially circular periphery 19 having notches or recesses at a plurality of points 20 that respectively correspond to the "off" and the several operating positions of the controller drum, as indicated by the reference letters in Fig. 2.

Assuming the pin member 17 to be resting in the cam plate recess 20 that corresponds to the "off" position of the controller drum, the operation of the apparatus just described may be set forth as follows: If the controller handle 10 is moved in a clockwise direction, the cam plate 18 forces the pin member 17 to ride upon that portion of its periphery 19 which lies intermediate the recesses 20 respectively corresponding to the "off" and the first operative position of the controller drum. The valve member 16 is thus opened to admit fluid pressure beneath the surface of the lubricating material 17, whereupon a highly attenuated lubricating medium, that is to say, lubricating material in the form of spray, is ejected from the several openings 13 in the pipe 6 upon the several contact segments 3, just prior to the engagement therewith of the control fingers 4. However, as soon as the first operative position of the con-

troller drum is reached, the pin 17 of the valve 16 drops into the corresponding recess 20 in the cam plate 18, and the valve member 16 is thus again closed to prevent the further disposal of lubricating material on the contact segments. This operation is repeated as the controller drum is moved from one operative position to another.

Reference may now be made to Fig. 4, which, in addition to the controller drum, the lubricant-containing vessel 5 and the pipes 6 and 15, comprises an electrically interlocking member 21 and a normally closed valve member 16^a that is interposed in the pipe 15. An outwardly-extending, movable projection 22 of the valve is adapted to act as the core of an actuating coil 23 that may be connected through a pair of control fingers 24 bearing upon the peripherally disposed contact segment 25 of the electrically interlocking member 21, the coil being energized from a battery (not shown) or in any other suitable manner.

The interlocking member 21 has its contact segment 25 provided with a plurality of openings or spaces 26 that are filled with insulating material, which openings or spaces respectively correspond to the "off" and the operative positions of the controller drum and are collectively disposed in the plane of one of the control fingers 24.

A brief description of the operation of this modification of my invention is all that is necessary: The actuating coil 23 of the valve 16^a is deenergized when the controller occupies its "off" position, and the valve member 16^a is thus closed. When the controller drum is moved toward its first operative position, the contact segment 25 bridges the control fingers 24, thereby completing the energizing circuit of the actuating coil 23 and effecting the opening of the valve 16^a, to permit the disposal of lubricating material on the contact segments 3, in a similar manner to that described in connection with Fig. 1. When the controller drum reaches its first operative position, the circuit of the actuating coil 23 is interrupted at the corresponding opening 26 of the contact segment 25, and the valve is again closed. It will be appreciated that this operation is duplicated as the controller is moved through its successive operative positions.

I do not wish to be restricted to the specific structural details or arrangement of parts herein set forth, as various modifications thereof may be made within the spirit

and scope of my invention. I desire, therefore, that only such limitations shall be imposed as are indicated in the appended claims.

I claim as my invention:

1. The combination with a plurality of coöperating stationary and movable contact members, of a lubricant-containing vessel, means for forcing a gas through the lubricant in said vessel and discharging it in the form of spray, against the contact surfaces of said movable member, and means for permitting said discharge only when the movable member occupies certain positions.

2. The combination with a rotatable controller drum provided with a plurality of contact segments, and a plurality of control fingers respectively coöperating therewith, of a lubricant-containing vessel, a source of compressed air, means for conducting the air through the lubricant and discharging it against the surfaces of the contact segments in the form of spray, a controlling valve disposed intermediate said source and said vessel, and interlocking means adapted to open said valve only when said controller drum occupies certain positions.

3. The combination with a rotatable controller drum adapted to assume an "off" position and a plurality of operative positions and provided with a plurality of contact segments, and a plurality of control fingers respectively coöperating therewith, of a lubricant-containing vessel, a source of compressed air, a pipe for conducting the air beneath the surface of the lubricant, a second pipe having a plurality of openings respectively disposed adjacent to said contact segments to discharge lubricant, in the form of spray, against the contact surfaces adjacent to said fingers, a valve disposed in said first pipe and normally biased to prevent the flow of air therethrough, and interlocking means actuated by the controller drum for actuating said valve to open position when the drum is being moved from its "off" position to its first operative position and from one to another operative position.

In testimony whereof, I have hereunto subscribed my name this 10th day of Dec. 1914.

ARTHUR J. HALL.
